UNITED STATES PATENT OFFICE.

PAUL A. GSTALDER, OF WILLIAMSPORT, PENNSYLVANIA, ASSIGNOR TO RADIANT STEEL PRODUCTS COMPANY, OF WILLIAMSPORT, PENNSYLVANIA, A CORPORATION OF DELAWARE.

DESIGN FOR A REGISTER INCLOSURE.

Application filed August 11, 1928. Serial No. 27,795. Term of patent 3½ years.

To all whom it may concern:

Be it known that I, PAUL A. GSTALDER, a citizen of the United States, residing at Williamsport, in the county of Lycoming and State of Pennsylvania, have invented a new, original, and ornamental Design for Register Inclosures, of which the following is a specification, reference being had to the accompanying drawing, forming part thereof.

Figure 1 is a perspective view of a register enclosure showing my new design.

Figure 2 is a top plan view of same.

I claim:

The ornamental design for a register enclosure, as shown.

PAUL A. GSTALDER.
